BROR ERIC DAHLGREN, OF CHICAGO, ILLINOIS.

DESIGN FOR A BOOKREST.

Application filed February 13, 1928. Serial No. 25,426. Term of patent 14 years.

To all whom it may concern:

Be it known that I, BROR ERIC DAHLGREN, a citizen of the United States, residing at Chicago, in the county of Cook and State of Illinois, have invented a new, original, and ornamental Design for Bookrest, of which the following is a specification, reference being had to the accompanying drawing forming a part thereof.

Fig. 1 of the drawing is a perspective view of the bookrest viewed almost directly from

the front so as to present it nearly in front elevation; Fig. 2 is a perspective view of the same viewed from the side, showing more clearly the supporting rear leg; and Fig. 3 is a perspective view of the same, on a smaller scale viewed from a point intermediate of the other two.

I claim:

The ornamental design for a bookrest as shown.
